UNITED STATES PATENT OFFICE.

JOSEPH R. PHELAN, OF OKLAHOMA CITY, OKLAHOMA.

BROODER STOVE.

Application filed March 30, 1926. Serial No. 98,456.

My invention relates to brooder stoves.

The object of my invention is the production of a device of the character described, which will be capable of utilizing a large percentage of the heat units usually escaping without heat extraction, and of evenly circulating the heat for a sufficient length of time to thoroughly extract for utilization said heat units; which will have the additional effect of so circulating said heat that it will not be influenced by strong currents or drafts, to such an extent as to cause the heat producing means to become extinguished and the object of the brooder to be defeated; which will not cause the pipes and flues to become so clogged as to shut off the even circulation of the heat; which will prevent the draft becoming so strong as to overheat the space sought to be evenly heated; which will be cheap in construction and manufacture, and easily manipulated, and efficient for the purposes intended.

Other objects and novel features, of the invention will further appear from the specification, claims, and one-sheet accompanying drawing, of which,

Figure 1 is an elevation of the device mounted on the fire pot, and a part of the divisions dotted-in; Figure 2 is a perspective view of the device separate from the fire pot and showing the circulation of the heat currents and the divisions in dotted-in portions; Figure 3 is a separate perspective view of the fire pot.

Like characters of reference designate like parts in all the figures.

The brooder stoves on the market today are all, or practically all, subject to the very serious following objections: that of an irregularity of circulation; excessive drafts and air currents which cause the burners to become extinguished. Many times, this happens at night, or when no one is in immediate attendance at the brooder. This causes the brooder to become cold and the chicks to be chilled, and injured or actually frozen; another common trouble is the too great draft and the changing air currents which causes the heating means to overheat and to injure the chicks.

It is believed these and other failures of the present brooder stoves are remedied by my invention. The application of the burner, whether of oil, gas, wood, coal, or other heat is not claimed as a part of this invention.

The device consists of a fire pot 2, on legs 1, having a door 3, with hinges 4, holding same to the fire pot, controlled partially by opening and shutting draft vent 5; the door is fastened and opened by latch 6 on clasp 7; the inside portion of the fire pot is shown at 8 and the cut-away portion near its upper edge is shown at 9. 10 designates the supply pipe, (one means of supplying fuel for the heating of the stove); and 10¹ designates an over-flow pipe. The lower section of the heating drum surrounding the fire pot 2 is designated by 11 and has a door 18, hinged at 19, and closed by latch 20, on clasp 21; the upper section of the heating drum 23 has a door 24, with hinges 25, fastened with latch 26, and clasp 27; the division between the upper and lower sections is shown by 22; the shoulder between the upper portion of the fire pot 2 and the outer edges 30 of the central drum in the upper sections is shown at 29, their joining is shown at 28; the outer wall of said upper central drum at 30; and the top of the device at 31.

It will be seen upon the application of heat, by oil, gas, coal, or other fuel, in the fire pot 2 and the opening of the draft regulating means 5 the heat current, from such style of heater as is selected will ascend 85 through the fire pot 2. The lower outer portion of heating drum 11 will receive such of the heat as is externally radiated from the fire pot; the lower heating drum 11 will also receive such heat as is radiated therein from 90 the outside of the pipe portion of the fire pot 2 and the heating drum 23 will receive such heat as is radiated therein from shoulder 29 and from the outside surface 30 of the inside heating drum. The lower section 95 of the heating drum 11 causes a greater amount of heat to be radiated towards the floor which is the space sought to be heated; and if desired a flange may be depended downwardly and outwardly from its outer edge, but this is not claimed as a part of this invention. The main part of the heat, however, will be received from the fire pot 2, through opening 9. The heat from that source enters the inside of heating drum 11 100 and strikes the outer wall thereof opposite opening 9. It is prevented by baffle 13 from immediately entering the outer flue 17 from that direction and is forced to move along the lines of the arrow 12, inside said lower section 11 and around the upper portion of the fire pot 2 in the direction further indi-

cated by arrows 12, until the current strikes the other side of said heat baffle 13 and is permitted to rise through opening 13^a in division between lower heating drum 11 and heating drum 23. Here it is again prevented by baffle 15 from immediately making exit from that point through pipe 17 and is forced to continue along the line indicated by arrows 14, around the upper central heating drum 30 until it strikes the opposite side of baffle 15 where it is now permitted to enter pipe 17 as it follows the line of arrows 16, 16, and passes out of pipe 17.

From the description and the accompanying one sheet drawing, and the specification, the advantages of construction, application and manufacture will be apparent to those skilled in the art to which my invention pertains. I have entered into a detailed description of the construction and relative arrangement of the parts embraced in the present and preferred embodiment of my invention in order to impart a full, clear and exact understanding of the said embodiment. I do not desire, however, to be understood as confining myself to the specific construction and relative arrangement of parts inasmuch as in the future practice of the invention various changes and modifications may be made such as fall within the scope of my invention as defined in my appended claims.

Having thus described the invention, what is claimed and desired to be secured by Letters Patent, is:

1. A brooder stove of the character described and for the purposes stated, comprising a fire pot with an outer door and a draft control therein, an opening in its upper part, a second smaller heating drum thereover, a third, and larger double and divided heating drum surrounding a portion of said fire pot and all of said second heating drum, an outer door in the lower and upper sections thereof, an upright closed heat baffle in the lower section, an opening in the partition between the said lower and upper sections; an upright closed heat baffle in the upper section, a flue, and an opening in the upper periphery of the said upper section entering same; all substantially as described.

2. A brooder stove for the purposes stated, comprising an upright cylindrical fire pot, side opening near its top, a second smaller heating drum thereover, a third and larger

double chamber surrounding part of said fire pot and said second heating drum and thereabove, its periphery extending considerably beyond the periphery of said fire pot, its center composed of the outer wall of a part of said fire pot, and the outer wall of a second heating drum thereover; an outer door in each lower and upper section, a heat baffle in its lower section, an opening in the partition between the lower and upper section; a heat baffle in the upper section; an opening in the upper portion of the outer wall of said upper section adapted to open into a flue, and a flue; all substantially as described.

3. The combination with a heat producing means of a brooder stove of the character described and for the purposes stated, comprising a fire pot with an outer door and a draft control therein, an opening in its upper part, a second smaller heating drum thereover, a third, and larger double and divided heating drum surrounding a portion of said first and all of said second heating drum, an outer door in the lower and upper sections thereof, an upright closed heat baffle in the lower section, an opening in the partition between the said lower and upper sections; an upright closed heat baffle in the upper section, a flue, and an opening in the upper periphery of the said upper section entering same; all substantially as described.

4. The combination with a heat producing means of a brooder stove for the purposes stated, comprising an upright cylindrical fire pot, a side opening near its top, a second smaller heating drum thereover, a third and larger double chamber surrounding part of said fire pot and said second heating drum and thereabove, its periphery extending considerably beyond the periphery of said fire pot, its center composed of the outer wall of a part of said fire pot, and the outer wall of a second heating drum thereover; an outer door in each lower and upper section, a heat baffle in its lower section, an opening in the partition between the lower and upper section; a heat baffle in the upper section, an opening in the upper portion of the outer wall of said upper section adapted to open into a flue, and a flue; all substantially as described.

JOSEPH R. PHELAN.
